Primary Examiner — Cynthia Ramirez(74) *Attorney, Agent, or Firm* — Margaret Polson; Oppedahl Patent Law Firm LLC(57) **CLAIM**

The ornamental design for a cart, as shown and described.

DESCRIPTION

FIG. 1 is a front perspective view of my new design for a cart. FIG. 2 is a side elevation view of the right and left sides, which are mirror images, of FIG. 1.

FIG. 3 is a front side elevation view of FIG. 1.

FIG. 4 is a back side elevation view of FIG. 1.

FIG. 5 is a top plan view of FIG. 1.

FIG. 6 is a bottom plan view of FIG. 1; and,

FIG. 7 is a front perspective view of the cart of FIG. 1 with an optional child seat, the only difference being the presence of the child seat, all other elements being the same.

The features shown in broken lines in the drawing depict environmental subject matter only and form no part of the claimed design.

1 Claim, 7 Drawing Sheets(56)
